UNITED STATES PATENT OFFICE.

EDWIN H. WILKINSON, OF OMAHA, NEBRASKA.

IRONING TABLE.

Application filed January 12, 1922. Serial No. 528,609.

To all whom it may concern:

Be it known that EDWIN H. WILKINSON, citizen of the United States, residing at Omaha, in the county of Douglas and State of Nebraska, has invented certain new and useful Improvements in Ironing Tables, of which the following is a specification, reference being had therein to the accompanying drawings.

10 The invention relates to ironing tables, and has for its object to provide a device of this character wherein the table may be easily and quickly adjusted to different heights according to the size of the person using the same, and the ironing table as a whole easily and quickly collapsed into a compact package for storage purposes. Also to provide a collapsible ironing table wherein it will be possible for users to place 20 their feet underneath the table thereby allowing ironing while seated.

A further object is to provide a foldable ironing table, which table is so constructed that when in position for use, a rigid and permanent structure is provided which is 25 free from wobbling or movement during an ironing operation.

A further object is to provide an ironing table comprising a top, downwardly inclined 30 legs pivoted to the underside of the top substantially centrally thereof, braces cooperating with guide members carried by the under face of the ironing board and having a gravity actuated detent cooperating with 35 notches in the under face of the ironing board, the lower ends of said legs being provided with connecting bars which are pivoted to said legs, said connecting bars having pivotally connected to their outer ends 40 upwardly and inwardly extending legs, which legs are provided with transversely disposed bars adapted to be received by a groove or channel on the under side of table top and forming means for supporting the 45 table top at various distances from the floor.

With the above and other objects in view the invention resides in the combination and arrangement of parts as hereinafter set forth, shown in the drawings, described and 50 claimed, it being understood that changes in the precise embodiment of the invention may be made within the scope of what is claimed without departing from the spirit of the invention.

55 In the drawings:

Figure 1 is a side elevation of the ironing

table, showing the same in one position for use and showing the table top adjusted at a different distance from the floor and the parts in dotted lines.

60 Figure 2 is a bottom plan view of the ironing table, showing the parts in collapsed positions.

Figure 3 is an enlarged longitudinal sectional view through the table top showing 65 the gravity actuated detent.

Figure 4 is a bottom perspective view of the front end of the board showing the brace and detent.

70 Figure 5 is a perspective view of the sleeve board.

Referring to the drawings, the numeral 1 designates the top of an ironing table and 2 downwardly and forwardly extending 75 spaced legs, which legs are pivotally connected at 3 to a bracket 4 secured to the underside of the top 1. The bracket 4 is preferably located adjacent the center of the top 1, and the legs 2 are connected together at their lower ends by means of a transversely disposed rod, and intermediate their length by cross braces 6. The legs 2 are provided with a transversely disposed bar 7, to which is pivotally connected at 8, the lower ends of upwardly and outwardly extending braces 11 which braces when held 80 against movement as hereinafter set forth will prevent movement of the legs in relation to the top 1. Braces 11 at their upper ends are pivoted at 12 to the outer ends of 85 a transversely disposed bolt 13, which bolt extends through elongated slots 13a in guide bars 14 and through the ends of the braces, therefore it will be seen that when the clamping operation takes place by tightening 90 the thumb nut 14a, the braces 11 will be held against movement and consequently the ironing table rigidly held in any position to which it may have been moved or adjusted. Pivotally mounted on the bolt 13 100 between the guide bars 14, is a gravity actuated block 15, which block is provided with a detent 16, which detent normally engages the under face 17 of the top 1 and automatically cooperates with notches 18 in the under face of the top 1 thereby maintaining the top 1 in any raised position to which it may have been moved during an adjusting operation.

105 Pivotally connected to the rod 5 carried by the legs 2 are rearwardly extending spaced connecting bars 19, which bars have 110

pivotedly connected at 20 to their outer ends, upwardly extending spaced legs 21, which legs have their upper ends connected together by transversely disposed rods 22. 5 The rods 22 are adapted to be received in a transversely disposed groove or channel 23 in the under face of the table top 1 adjacent its rear end, at which time the legs 21 are received in the recesses 24 in the table 10 top. After the desired rod 22 has been placed in position in the groove or channel 23 for properly positioning the top 1 in relation to the floor, pivoted members 25 are moved to positions across the groove or 15 channel 23 for holding the rod 22 in the groove thereby preventing displacement of the table top during an ironing operation.

It will be seen that during an ironing operation the supporting structure, particularly 20 the braces 11 legs 2 and 21 and connecting brace 19 will brace the table in such a manner that the table will be prevented from wobbling or moving and that the table top will be rigidly supported. It will be 25 also seen that by adjusting the braces 11 and placing the detent 16 in any of the notches 18 that the table top 1 may be adjusted to different positions in relation to the floor, thereby 30 accommodating the board to the height of the operator. By eliminating braces usually employed in ironing tables between the legs 2 and 21, and providing 35 bars 19 at the lower ends of same it will be seen that the feet and legs of the operator may be placed under the table top during an ironing operation, thereby allowing the operator to iron while seated.

The rear end of the table top 1 is provided 40 with a notch 26, which notch receives a shank 27 of a bolt, said bolt being provided with a butterfly nut 28 at its lower end and with a sleeve board 29 at its upper end. After the bolt 27 has been placed in the notch 26, the sleeve board may be securely held in place by tightening the butterfly nut 28. When the device is not in use and it is desired to collapse the same, nut 14^a is loosened, thus allowing the braces 11 to be

50 moved into position shown in Figures 2 and 3, bolt 13 sliding forward in elongated slot 55 13^a then the legs 21 are disconnected at their upper ends from the top 1 and allowed to hinge downwardly between the bars 19, at which time the legs 2 are folded onto the bottom of the top 1 and the legs 21 and connecting bars 19 onto the rear side of the legs 2 at which time the parts will be folded as shown in Figure 2. The under face of the top 1 is provided with a hook 30 which hooks over one of the rods 22 as clearly 60 shown in Figure 2 when the table is collapsed, thereby firmly holding the supporting leg structure in collapsed position. Disengagement of detent 16 from notches 18 on under face of ironing board 1 is accomplished by raising the rear edge of block 15. 65

The invention having been set forth what is claimed as new and useful is:—

An ironing table comprising a top, spaced legs pivoted to the under side of said top at 70 points spaced from its ends, a brace pivotally and slidably connected to the under side of said top, and at a point spaced from its under face, said brace extending downwardly and having its lower end pivotally 75 connected to the pivoted legs, connecting bars pivoted to the lower end of said legs and terminating beyond the rear end of the table top, upwardly and inwardly extending legs pivoted to the rear ends of said 80 connecting bars, transversely disposed rods carried by said last named legs and adapted to be received by a transversely disposed groove in the under face of the rear end of the table top, means for maintaining said 85 rods in said groove, means for holding said top in various positions, said means comprising a gravity actuated detent cooperating with notches in the under face of the top, said gravity actuated detent being carried 90 by a clamping bolt, and held against movement thereby when tightened.

In testimony whereof I hereunto affix my signature.

EDWIN H. WILKINSON.
